KNOTTER FOR TWINE BALERS

Robert H. Collins, Brownsville, Oreg.

Application February 24, 1954, Serial No. 412,268

8 Claims. (Cl. 289—14)

This invention relates generally to binders and particularly to an improved knotter for twine balers.

The main object of this invention is to provide a binder which will satisfactorily handle large sizes of twine such as are used as a substitute for wire in baling hay and straw.

The second object is to encourage the use of twine binders for baling hay and straw instead of wire, which is dangerous to stock, especially if run through a chopper.

The third object is to so modify the twine holder to adapt it to use with large sizes of twine without injury to the twine.

The fourth object is to provide a twine guard to prevent the splitting of the twine as disk 15 is revolved with the twine under high tension as is required with twine baling.

The fifth object is to make it possible to compete with wire baling as to cost of baling, the amount of hay held within a bale of given size, and at the same time avoiding the use of steel, which is often required for other purposes. In addition thereto, the serious objection to wire baling as being injurious to cattle is overcome as the twine ties are cut into safe lengths by the chopper.

I accomplish these and other objects in the manner set forth in the following specification as illustrated in the accompanying drawings, in which

Fig. 1 is a diagrammatical sectional view, showing the essential elements showing the first step in the making of a bale.

Fig. 2 is similar to Fig. 1, showing the bale completed and the needle in a raised position.

Fig. 3 is similar to Fig. 2, showing the knot tied and the needle returning to the position of rest and the plunger returning for a new charge of hay.

Fig. 4 is an enlarged fragmentary section taken along the line 4—4 in Fig. 2.

Fig. 5 is a fragmentary perspective of the knotter head.

Fig. 6 is an enlarged section taken along the line 6—6 in Fig. 5.

Fig. 7 is an enlarged developed section along the center line 7—7 in Fig. 13.

Fig. 8 is an enlarged section taken along the line 8—8 in Fig. 12.

Fig. 9 is an enlarged section taken along the line 9—9 in Fig. 12.

Fig. 10 is an enlarged perspective view of the twine guard.

Fig. 11 is an enlarged perspective view of the twine holder.

Fig. 12 is a section taken along the line 12—12 in Fig. 6.

Fig. 13 is a section taken along the line 13—13 in Fig. 6.

Fig. 14 is similar to Fig. 13 except that the clamp disk has moved partially toward the twine holder.

Fig. 15 is similar to Fig. 14 except that further movement is shown. As pressure on the twine is increased, the twine can slip through under approximately a forty-pound pull.

2

Fig. 16 is similar to Fig. 15 except that the knotting is complete except for stripping and cutting.

Fig. 17 is similar to Fig. 16 except that further rotation has brought the disk 39 to rest with the maximum pressure on the twine.

Fig. 18 is an enlarged perspective view of the stripper plate and cutter knife.

Fig. 19 is a perspective view in reduced scale of the completed bale.

10 Referring in detail to the drawings, there is shown in Figs. 1, 2 and 3 a somewhat diagrammatic layout of four of the possible positions of the basic elements in the baler comprised of a pair of side frames 20, which support a chamber floor plate 21. A twine box 22 is shown on the plate 21 and a heavy twine 23 from the box 22 passes over the sheaves 24, 25 and 26. A weighted pulley 27 rides on the twine 23 between the sheaves 25 and 26. This is merely a tension device. The twine 23 then passes around the pulleys 28 and 29, between which is placed 20 a friction tension brake 30.

In the floor plate 21 are formed the slots 31, through which can pass the needle arms 32 which are mounted on a common shaft 33 and is operated by a crank (not shown).

25 On the floor plate 21 rides the plunger 34 having slots 35 formed therethrough in the planes of said needles 32. Means (not shown) are provided for reciprocating the plunger 34 through a piston 36.

In Fig. 1 the needle arm 32 is shown in the down, 30 or retracted, position below the level of the plate 21. The twine 23 passes from the pulley 29 through the needle 32 and out of its point 37 to the disk assembly 38. The disk assembly includes the disk 39, which is a part of the shaft 40. To the disk 39 is secured the disk flange 41 by means of the rivets 42. In the groove 43 formed between the parts 39 and 41 is a twine holder 44 having a hole 45 at one end for a pivot screw 46 by means of which it is attached to the knotter assembly frame 47.

The disk 39 has formed around its circumference a rim 48, on the inner side of which is formed a narrow groove 49 in which can ride the arcuate end 50 of the twine guard 51, which is fastened to the frame 47 by means of screws 51-A. This is one of the distinguishing features of my invention.

In the outer portion of the disk 39 are the pockets or notches 52. The flange 41 has corresponding pockets or notches 53.

A pinion 54 is secured on the shaft 40 and meshes with the worm 55 on the shaft 56 on whose upper end is secured a pinion 57 which meshes with the intermittent gear 58 on the shaft 59 which journals in the bearing 60 which is part of the knotter frame 47.

The shaft 59 is driven in the manner usual in knotting devices of this type.

55 The twine holder 44 is formed with a slot 61 along one edge thereof. The edge 62 is arcuate in shape on a single radius, whereas one-half of the edge 63 is arcuate to conform to the edge 62 while the remainder 64 of the edge 63 is at a somewhat larger radius in order to permit slipping 60 of the twine while the knot is being tied.

Attention is drawn to Fig. 7, which is a development of the disk circle. It will be noted in this figure that the lobes 65 between the pockets 52 and 53 are rounded along their edges as illustrated, the purpose of which is to prevent undue wear and breakage of the twine.

The positions of the twine 23 at the various pockets, or stations, 52 and 53 are indicated. These are five in number.

Opposite the twine holder 44 and occupying space between the disk 39 and flange 41 is the arcuate face 66 of the twine disk cleaner 67 whose end 68 is recessed to conform somewhat to the trailing end of the pockets 53

(Fig. 13). On the cleaner 67 is formed a shank 69 which occupies a slot 70 in the frame 47. Secured to the frame 47 by means of a screw 71 is a leaf spring 72 which bears against the ear 73 on the twine holder 44.

In Fig. 18 is shown a portion of the end of the twine knife arm 74 mounted on the pivot 75 and said arm 74 has on its end a cam roller which engages a cam, neither of which are shown as they are common to all knotters. The cam is formed on the hub 76 and merely sweeps past the roller end of the arm 74.

Secured to the arm 74 is a stripper plate 77 having an arcuate notch 78 formed in its end which fits snugly against the back 79 of the knotter bill hook 80, while the sides 81 extend along the sides of the hook 80 and serve to better remove the knot therefrom. The knotter bill hook 80 is driven by a pinion 82 which meshes with the segment gear 83.

The finger 84 is pivotally mounted on the hook 80 and has on the end thereof a roller 85 which engages the cam surface 86 formed on the frame 47.

A spring loaded knotter hook cam 87 urges the finger 84 toward a twine holding position and pulls the loop through the knot being formed.

The knotter operation is well understood by those familiar with the art and is referred to here only to form a basis for the explanation of the improvement. It will be understood that the principles set forth herein apply to the tying of a three-string bale 88 as it would on a two-string bale.

The position of the cutoff blade 89 on the arm 74 is also indicated.

The first point of improvement lies in the tripling in thickness of the disk 39, making it possible to provide an easy turning radius for the face 90 as compared with the abrupt angular faces on the disks used on other types of twine knotters now in use. It will be noted that the corners 91, 92 and 93 are also rounded to reduce injury to twine as it passes through the knotter.

Attention is drawn to Fig. 9 in which is shown the improved form of twine guard 51 which rides in the groove 49 and makes it impossible for the strands of the twine to become caught by the guard 51.

Turning now to Fig. 11, showing the twine holder 44, it will be noted that face 62 is a continuous curve on one radius while the curve 63 is offset on two radii to secure an easement in the tension when most needed.

I claim:

1. In a knotter disk assembly, the combination of a shaft, a knotter disk on said shaft having pockets formed around the circumferential edge thereof, said disk having a right angle flange around the space between said pockets and having formed therein just inside of said flange a narrow groove, one side of which coincides with the inner side of said flange, and an arcuate twine guard fitting into said narrow groove and having means for supporting same in a fixed position.

2. In a knotter disk assembly, the combination of a knotter disk and a disk flange having a common shaft mounting therefor and having a channel formed therebetween, a stationary twine cleaner having a blade occupying a portion of said channel, said knotter disk having a laterally extending flange, both disk and flange having pockets formed in their circumference, said knotter disk having a narrow groove formed in its face adjacent said lateral flange, and a stationary twine guard having an arcuate blade extending into said narrow groove to prevent strands of the twine from becoming caught between said knotter disk and associated parts.

3. In a twine knotter assembly, a disk having opposed face surfaces and having a plurality of peripheral notches for receiving twine, and a peripheral flange between said notches on said disk projecting beyond one of said face surfaces of said disk, said one face surface being provided with an annular groove adjacent said flange for receiving guide means for said twine.

4. In a twine knotter assembly having bill hook means for tying a knot, a rotatable disk having notches in its peripheral edge for receiving twine leading from said bill hook, said disk having opposed face surfaces and having an annular groove in one of said face surfaces, a twine guard engageable in said groove and adapted to guide twine into said notches, a twine holder engageable with said disk and adapted to cooperate therewith in holding twine in said notches when said bill hook is performing a knot tying operation, and a stripper plate for positively removing said knot from said bill hook at the completion of a knot tying operation.

5. In a twine knotter assembly having bill hook means for tying a knot, a rotatable disk having notches in its peripheral edge for receiving twine leading from said bill hook and having a face groove adjacent its periphery, a twine guard having an angular blade portion extending into said groove for guiding twine into said notches, a twine holder engageable with said disk and adapted to cooperate therewith in holding twine in said notches when said bill hook is performing a knot tying operation, and a movable stripper plate having an arcuate notch conforming in shape to a rounded portion of said bill hook for slidably engaging said bill hook and positively removing said knot from said bill hook at the completion of a knot tying operation.

6. In a twine knotter assembly having bill hook means for tying a knot, a rotatable disk having notches in its peripheral edge for receiving twine leading from said bill hook and having a face groove adjacent its periphery, a twine guard having an angular blade portion extending into said groove for guiding twine into said notches, a twine holder engageable with said disk and adapted to cooperate therewith in holding twine in said notches when said bill hook is performing a knot tying operation, and a movable knife for cutting said twine after a knot has been formed, and a stripper plate movable with said knife, said stripper plate having an arcuate notch conforming in shape to a rounded portion of said bill hook for slidably engaging said bill hook and positively removing said knot from said bill hook.

7. In a twine knotter assembly, a disk having opposed face surfaces and having a plurality of peripheral notches for receiving twine, and a peripheral flange between said notches projecting beyond one of said face surfaces of said disk, said one face surface being provided with an annular groove adjacent said flange for receiving guide means for said twine, the inner peripheral wall of said flange being coextensive with the outer wall of said groove.

8. In a twine knotter assembly, a disk having a plurality of peripheral notches for receiving twine, and a peripheral flange between said notches projecting at right angles beyond one face of said disk, said disk having a face groove adjacent said flange for receiving guide means for twine.
